(57) **CLAIM**

The ornamental design for a track lighting fixture, as shown and described.

DESCRIPTION

FIG. 1 is an isometric view of one embodiment of the present invention;

FIG. 2 is a right side view of the embodiment shown in FIG. 1;

FIG. 3 is a left side view of the embodiment shown in FIG. 1;

FIG. 4 is a bottom view of the embodiment shown in FIG. 1 without a lamp;

FIG. 5 is a top view of the embodiment shown in FIG. 1 without a lamp;

FIG. 6 is a front view of the embodiment shown in FIG. 1 without a lamp;

FIG. 7 is a rear view of the embodiment shown in FIG. 1 without a lamp;

FIG. 8 is an isometric view of another embodiment of the present invention;

FIG. 9 is a right side view of the embodiment shown in FIG. 8;

FIG. 10 is a left side view of the embodiment shown in FIG. 8;

FIG. 11 is a bottom view of the embodiment shown in FIG. 8 with lamps;

FIG. 12 is a top view of the embodiment shown in FIG. 8 without lamps;

FIG. 13 is a front view of the embodiment shown in FIG. 8 without lamps; and,

FIG. 14 is a rear view of the embodiment shown in FIG. 8 without lamps.

The broken lines shown in the Figures illustrate exemplary lamps that form no part of the claimed design.
